FIG. 3.

FIG. 4.

FIG. 5.

WITNESS:

P. R. Kitchel.

INVENTOR

Emanuel Louis Middleman

BY

Bauser & Harding
ATTORNEYS.

UNITED STATES PATENT OFFICE.

EMANUEL LOUIS MIDDLEMAN, OF PHILADELPHIA, PENNSYLVANIA, ASSIGNOR, BY MESNE ASSIGNMENTS, OF ONE-HALF TO ROSENAU BROS. INC., OF PHILADELPHIA, PENNSYLVANIA, A CORPORATION OF PENNSYLVANIA, AND ONE-HALF TO EINHORN BROTHERS, A COPARTNERSHIP COMPOSED OF BENJAMIN EINHORN, FRANK EINHORN, AND SAMUEL LOUIS EINHORN, ALL OF PHILADELPHIA, PENNSYLVANIA.

CHILD'S ROMPER.

Application filed July 27, 1926. Serial No. 125,163.

My invention relates to an improvement in children's rompers or pants and more particularly to that portion of the romper or pants constituting the crotch.

5 Children's rompers such as are customarily produced, more particularly for wear by little children, are composed of a body having a back and front portion the lower ends of which are curved and secured together 10 by a seam, openings being left which when finished serve for passage of the legs. The portion between the leg openings forms the crotch portion of the garment.

15 Rompers or pants of the character to which my invention more particularly relates are subjected to substantial strain through the crotch and the seam therein frequently gives way.

20 Now it is the object of my invention to provide a structure for children's pants and more especially for the crotch seam thereof which will be reinforced in a novel and effective manner and which will be proof against strain to which it may normally be 25 subjected.

Having now indicated, in a general way, the nature and purpose of my invention, I will proceed to a detailed description thereof with reference to the accompanying drawings 30 in which there is illustrated a preferred embodiment and in which:—

Fig. 1 is a front view of a pair of children's rompers embodying my invention.

Fig. 2 is a detail view of the crotch seam 35 of the subject of Fig. 1 at a preliminary stage in its construction.

Fig. 3 is a sectional view on line 3—3 Fig. 2.

40 Fig. 4 is a sectional view of the crotch seam of the subject of Fig. 1 in the final stage of its construction.

Fig. 5 is a sectional view, on line 5—5 Fig. 1, showing the completed crotch seam.

45 The rompers or pants comprise a front portion *a* behind which is a similar rear or back portion *a'*. The front and back portions are provided with waist bands *b* and they are secured together along their sides, to a point near the waist bands. The waist bands are provided with buttons and button holes *c*, respectively, by which the ends 50 of the waist bands may be secured together

and the rompers or pants retained on the wearer. The central portions of the lower edges of the front and back portions are secured together to form a crotch portion, while the end portions are left unsecured and when finished with bands *d*, or hemmed, form openings for the passage of the 55 wearer's legs.

60 So far as the garment shown in the drawings has been described, the structure is typical of such garments. However, in accordance with my invention I form the seam at the lower end or crotch portion of the garment in a novel and highly efficient manner 65 and the structure of which I will now describe in detail.

65 In forming the crotch seam the lower ends *e*, *f*, of the front and back portions of the 70 garment are overlaid and a cord *g* laid on the front portion adjacent its lower end. The lower ends of the front and back portions and the cord are secured together by means of a line of stitching *h*. The structure thus formed is clearly shown in Figures 75 2 and 3.

The garment is now reversed or turned inside out, and the front and back portions secured together by a line of stitching *i* in so general parallelism with the line of stitching *h* and just above the cord *g*. The structure thus produced will be clear from an inspection of Figure 4.

75 The garment is now again reversed, or 80 turned right side out, and the structure of the completed crotch seam will be understood from an inspection of Figure 5, in which it will be observed that the front and back portions of the garment are secured together and to the cord *g*, that they are brought around the cord *g* and again secured together and that finally each portion is brought around upon itself to give the 85 seam a finished appearance.

90 It will be understood that I do not intend that my invention shall be limited to the details of construction of the rompers or pants herein illustrated and described, since it is obvious that the structure of the 95 rompers may be varied in detail without departing from my invention. Further, it will be understood that while herein I have 100 described my invention in connection with

rompers that it may be applied effectively to various other garments.

Having now fully described my invention, what I claim and desire to protect by Letters Patent is:—

1. A garment having a body portion and leg openings, the garment being formed of sections united by seams including a seam extending between the leg openings, said 10 seam extending between the leg openings comprising at least three plies of material, two of which are the fabric of the garment, and the third a reinforcing strip, the three plies being united together by a line of 15 stitching, and a second line of stitching uniting portions of the fabric of the garment adjacent the reinforcing strip to form an enclosure for the edges of the sections of the garment and for the reinforcing strip.

2. A garment of the bloomer type having 20 body and leg openings, the garment being formed of sections united by seams, said garment being strengthened at and about its seam portions, the seams comprising at least three plies of material, two of which are 25 the fabric of the garment, and the third a reinforcing strip, the three plies being united together by a line of stitching, a second line of stitching uniting portions of the fabric of the garment adjacent the seam 30 to form an enclosure for the raw edges of the plies and the strip and impart additional strength adjacent the seam portions.

In testimony of which invention, I have hereunto set my hand, at Philadelphia, 35 Pennsylvania, on this 16th day of July, 1926.

EMANUEL LOUIS MIDDLEMAN.
